UNITED STATES PATENT OFFICE.

EDGAR B. STOCKING, OF WASHINGTON, DISTRICT OF COLUMBIA; SARAH C. STOCKING
EXECUTRIX OF SAID EDGAR B. STOCKING, DECEASED.

MATERIAL-ACTUATED RELEASE FOR CLOTHES-WRINGERS.

1,342,005.

Specification of Letters Patent.

Patented June 1, 1920.

Application filed March 6, 1917. Serial No. 152,886.

To all whom it may concern:

Be it known that I, EDGAR B. STOCKING, a citizen of the United States, residing at Washington, in the District of Columbia, 5 have invented certain new and useful Improvements in Material-Actuated Releases for Clothes-Wringers, of which the following is a specification, reference being had therein to the accompanying drawing.

10 This invention has relation to a pressure release for clothes wringers and it has for one of its principal objects the utilization of the thickness of clothes or other material after being operated upon, to determine the 15 normal feeding capacity of the wringer and at the same time to utilize an increase of said thickness as the means for actuating the release of the pressure producing means of the wringer to insure safety to the operator 20 and prevent over straining and deflection of the roller shafts by excessive feeding. Other objects and advantages of the invention will appear in the following description and the 25 novel features thereof will be particularly pointed out in the claims.

Referring to the drawings forming a part hereof and in which like reference numbers refer to like parts in all of the figures:

Figure 1 is a rear or delivery side elevation with parts in section of a wringer embodying the invention, and

Fig. 2 is a vertical section on the line 2—2 of Fig. 1.

The principal elements constituting a well known form of wringer comprise standards 35 1 in which are mounted a relatively fixed lower power driven roll 2 and an upper movable roll 3 each provided at each end with gears 4 and with their journals provided 40 with bearing-blocks 5, the upper one of which has a stud as shown for centering a main spring 6 upon which the pressure screws 7 bear and by which the pressure of the springs of the wringer is regulated to produce the desired pressure of the movable 45 roller upon the fixed roller. 8 is the usual delivery board and 9 the usual cross-board. The cross-bar 10 is movably supported in a recess formed at the top of each standard 50 and carries the pressure screws 7 and also carries spring hooks 11 which coact with stop wires or pins 12 and 13, the former to retain the pressure of the rolls and the latter to limit the upward movement of the cross-

bar when said pressure is released. In this 55 instance the spring hooks are arranged inside of the standards, being attached to the cross-bar in any suitable manner.

Taking the above as any ordinary wringer provided with means for permitting the release of the pressure of the rolls upon each other or upon the material between them, it now remains to describe the invention to be disclosed herein for releasing said pressure.

Above the delivery board is a roller 14 65 which is journaled at each end in slots 15 formed in the standards 1. A link 16 is slotted as at 17 to receive the journal of roller 14 and to permit the roller 14 to rise and fall a distance compatible with a normal 70 feed to the rolls; but if abnormal, then in that case, the journal of the roller contacts with the upper end of said slot 17 and the link 16 is thereby raised. It will be understood therefore that the slot 17 provides a 75 working space for the bearing of the roller 14 to accommodate different thickness of material, as it emerges from the wringer roll in a substantially uniform flattened condition, and serves as a somewhat accurate gage 80 to determine when abnormal feeding occurs and therefore a more accurate provision to determine when the release should be actuated.

As release devices are provided on each 85 standard there is provided a connecting plate 18 of light but rigid material each end of which is secured to the adjacent link 16 in order to maintain parallelism and simultaneous action of the links and parallelism 90 of the roller 14 with the delivery board, so that the abnormal thickness of material at either end of the roll will actuate both sets of releasing devices.

At 19 is pivoted a lever, 20 provided with 95 a wedge 21, adapted to coöperate with the spring hook 11, to disengage it from the stop pin or wire 12. This adaptation is accomplished by connecting the link 16 at 22, whereby when the roll 14 is raised beyond 100 the normal working space or slot 17, in the link 16 with its journals riding in the slots 15 of the standards, the lever forces the wedges 21 between the spring hooks 11 and the standards, thus releasing said hooks and 105 the pressure producing devices of the wringer. The pivot 22 of the connecting link 16 and the lever 20 is preferably screw

threaded in order that it may be rendered easily removable, so that the roll 14 may be raised, without operating the lever 20—if desired.

5 The wedge levers 20 are extended to the front side of the wringer and are connected by a rod which serves as a means of actuating the release manually, that is by a mere blow downwardly on said rod by the hand 10 of the operator. This provision is important in that no mechanism is absolutely infallible and therefore, by this manually operated adjunct release as in time of accident, is assured.

15 The operation of my improved material actuated release for clothes wringers is as follows: Wherein the material passes through the rolls of the wringer it leaves the rolls in a compressed flattened condition regardless of the thickness of the material, and as the releasing device is located adjacent the pressure rolls, the devices engaged by the abnormal thickness of the material so that the pressure is released quickly.

20 25 While I have shown one form of an embodiment of the invention it is to be understood that it may be arranged either inside or outside of the standards and combined with pressure producing and retaining 30 means other than that disclosed herein and may be changed in form, dimensions, proportions and relative arrangement to adapt it to such other pressure producing and retaining means and in all respects within 35 ordinary mechanical skill, without departing from the principle of the invention. It is also apparent that the roller 14 or its equivalent release actuating means might be arranged above the feed board of a wringer 40 by a mere reversal of the parts although it is preferably used in connection with the delivery board for reasons hereinbefore stated. Such a reversal of the parts is illustrated by assuming the delivery board 8 to 45 be the feed-board of the wringer.

What I claim is:

1. A wringer comprising a frame having pressure rolls and pressure means for said rolls, means for holding said pressure means 50 in predetermined position, levers for releasing said pressure retaining means, a bar connecting said levers at one end, a link carried by the opposite end of said levers, and a movable member carried by said links 55 arranged adjacent the bite of said pressure rolls.

2. In a clothes wringer having pressure rolls and pressure means for said rolls, means for holding said pressure rolls in predetermined position, and a movable member 60 arranged to one side of said pressure roll and adapted to be engaged by the material passing through said wringer, and means actuated by said movable member for releasing said pressure means by the pas-

sage of an abnormal thickness of material through said wringer.

3. A wringer comprising a frame having pressure rolls and pressure means for said rolls, yielding members for holding said pressure means in predetermined position, levers having wedge portions arranged to engage said yielding members, and means carried by said levers arranged to be engaged by an abnormal thickness of material 75 passing through the rolls for moving the wedge members of said levers into engagement with said yielding members for releasing said pressure means.

4. A clothes wringer comprising a frame 80 having pressure rolls and pressure means for said rolls mounted therein, a top bar having yielding members for holding said top bar in predetermined position, levers arranged to engage said yielding members 85 for releasing said top bar, and movable members operated by the passage of an abnormal thickness of material through said rolls for actuating said levers.

5. A clothes wringer having pressure rolls 90 and means for holding said rolls in contact under tension, means for releasing said rolls, and a member disposed to one side of said roll actuated by the passage of an abnormal thickness of material through said rolls for 95 actuating said releasing means.

6. A wringer, comprising a frame having pressure means, pressure retaining means at each end of said wringer, a lever pivoted at each end of the wringer having a wedge, 100 a bar connecting said levers at one end, a link carried by the opposite end of each of said levers having a slot, a movable member mounted in the slots of said link, means for guiding said movable member, and a 105 support arranged below said member.

7. A clothes wringer having pressure rolls and pressure means for said rolls, means for holding said pressure means in predetermined position, a material support, a movable member arranged in the path of travel of the material over said support, and a release actuated by said movable member 110 engaging said retaining means for releasing said pressure.

8. A clothes wringer, comprising a frame having pressure rolls and pressure means for said rolls, movable members for holding said pressure means in predetermined position, pivoted levers engaging said movable 120 members for releasing said pressure means, slotted links carried by said pivoted levers, and a member mounted in the slots of said links adapted to be engaged by an abnormal thickness of material passing through the 125 rolls of said wringer.

9. In a clothes wringer having pressure rolls and pressure means for said rolls, means for holding said pressure means in predetermined position, means co-acting 130

- with said pressure retaining means for releasing said pressure means, a goods support, a movable member arranged to one side of said pressure means, and above said goods support having a connection with said pressure releasing means, said movable member being adapted to operate said pressure releasing means by the passage of an abnormal thickness of material over said support.
- 10 10. A clothes wringer comprising a frame having pressure rolls, means for holding said rolls in contact under tension, a goods support, and means disposed above said goods support adapted to be engaged by the material passing through said rolls for releasing said tension means by the passage of an abnormal thickness of material over said support.
- 15 11. A clothes wringer, comprising a frame having pressure rolls, means for holding said rolls in contact under tension, levers for releasing said tension means, and levers connected with said means disposed to one side of said rolls for releasing said tension
- 20
- 25

means by the passage of an abnormal thickness of material under said means.

12. A clothes wringer, comprising a frame having pressure rolls, means for holding said rolls in contact under tension, levers for releasing said tension means, and a movable member carried by said levers disposed to one side of said rolls and adapted to be moved by the passage of an abnormal thickness of the goods under said member for releasing said tension means.

13. A clothes wringer, comprising a frame having pressure rolls, means for holding said rolls in contact under tension, levers for releasing said tension means, links carried by said levers, a goods support, a movable member carried by said links above said goods support and to one side of said rolls, and adapted to be operated by the passage of an abnormal thickness of material over said goods support.

In testimony whereof I hereunto affix my signature.

EDGAR B. STOCKING.
